UNITED STATES PATENT OFFICE.

JAMES A. LAKIN, OF WESTFIELD, MASSACHUSETTS.

VOCALIZING-AUDIPHONE.

SPECIFICATION forming part of Letters Patent No. 574,544, dated January 5, 1897.

Application filed October 22, 1896. Serial No. 609,704. (No model.)

To all whom it may concern:

Be it known that I, JAMES A. LAKIN, a citizen of the United States of America, residing at Westfield, in the county of Hampden and State of Massachusetts, have invented new and useful Improvements in Vocalizing-Audiphones, of which the following is a specification.

This invention relates to vocalizing-audiphones and similar devices for amplifying speech-sounds, which are adapted to be applied directly to the ear of a person for said purpose, the object being to provide an improved construction and arrangement of the devices of said instrument whereby articulate speech is rendered distinct and clear; and the invention consists in the construction and arrangement of the sound receiving and transmitting elements of the device, all as hereinabove fully described, and more particularly pointed out in the claims.

In the drawings forming part of this specification, Figure 1 is a longitudinal sectional view of a vocalizing-audiphone embodying my improvements. Fig. 2 is a front end view; and Fig. 3 is a similar view to Fig. 1, but illustrating the internal sound receiving and transmitting elements of the instrument from other points of view to the illustration thereof of Fig. 1. Fig. 4 is a perspective view of a detail part hereinafter described.

In the drawings, A indicates the main case part of the instrument, which is of circular concave form; and B the ear-tube, extending from said case. C is the perforated cover of the said part A. The said parts A, B, and C are made, preferably, of hard rubber, and said cover has a border 3, which has a tight spring-like engagement with a similar border on said case part A, whereby said cover is retained thereon. A dome-shaped element D is secured rigidly by its apex to the interior of the cover C, preferably by a rivet 4. Said element D I term the "vocalizing-chamber dome," and it is preferably of thin sheet metal of a dense or hard nature, whereby a resonant quality is imparted thereto.

The herein-described audiphone may consist simply of said case parts A, B, and C and said dome D, whereby good vocal effects are produced, or may comprise another element, below described, whereby said effects are in-

tensified. A receiving-chamber E for reflected sounds is provided within a hollow sound-receiver E², of conical form. Said receiver is also preferably made of thin sheet metal of a dense and resonant quality, and has its larger end secured to the inner surface of said dome D and its opposite or smaller end extending toward and preferably slightly within the end of the ear-tube B, where it joins said case part A. Said receiver E², while secured to said dome, as aforesaid, has in practice its border adjoining said dome standing away about one-sixteenth of an inch, more or less, from said dome, as shown in Figs. 1 and 3, and is supported in such position of separation by two narrow projections or posts 55, extending between said receiver and dome and secured by their extremities to the latter 70 by soldering or other suitable means, whereby said receiver is maintained permanently in said separated position, as shown.

The above-described audiphone construction and the arrangement of the parts of the same are found to amplify sounds to a great degree, which are received through the perforated cover C. The space inclosed by the case part A and the cover C is the vocalizing-chamber, and D is the said vocalizing-dome, 80 and within said conical element E² is said sound-reflecting chamber E. Thus within said case, as described, are provided said dome D and sound-receiver E², interconnected and both supported in said case by a single connection 4 with the said cover C, and thereby said parts D and E² are free for most advantageous resonant action induced by sound-waves passing through said cover thereagainst. Said resonant action is due to the movement of sound-waves substantially in the directions indicated by the several arrows shown in Fig. 3. That is to say, the sounds passing through the said cover C are received mainly against the outer side of said dome D 90 and against the concave surface of the said bowl-shaped part of the case A, from whence sound-waves are reflected upwardly into said dome and from there back into said receiving-chamber E, and thence into the ear-tube 100 B. Certain of said sound-waves received in said case A may pass by the dome D into said ear-tube, as indicated by certain of said arrows, amplified more or less by the action of

said dome; but the sharpest and most distinct tones are produced by their passage between the inner wall of the dome and the receiver E² and thence through the receiving-chamber E.

Having thus described my invention, what I claim, and desire to secure by Letters Patent, is—

1. A vocalizing-audiphone comprising a hollow case having an ear-tube extending from one side and a perforated cover applied to the opposite side thereof, combined with a dome of resonant material secured by its apex to the inner side of said cover, and a hollow cone-shaped sound-receiver connected by one end to the inner surface of said dome, but mainly separated therefrom, substantially as set forth.

2. A vocalizing-audiphone comprising a hollow case having an ear-tube extending from one side and a perforated cover applied

to the opposite side thereof, combined with a dome of resonant material attached by its apex, only, to the inner side of said cover, whereby the body thereof is free for resonant action, and a hollow cone-shaped sound-receiver of resonant material connected by one end to the inner surface of said dome, but mainly separated therefrom, substantially as set forth.

3. A vocalizing-audiphone comprising a hollow case having an ear-tube extending from one side and a perforated cover applied to the opposite side thereof, combined with a dome of resonant material secured by its apex to the inner side of said cover, substantially as set forth.

JAMES A. LAKIN.
